(57) **CLAIM**

The ornamental design for a tumbler assembly as shown and described.

DESCRIPTION

FIG. 1 is a perspective view of a tumbler assembly, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an exploded perspective view thereof.

The claim is directed to the collective appearance of a tumbler assembly—comprised of a tumbler with accompanying lid. The portions of the tumbler assembly shown in broken lines form no part of the claimed design.
